(57) CLAIM

An ornamental design for a medication label flag, as shown and described.

DESCRIPTION

FIG. 1 is a rear elevation view of the medication label flag showing our new design;

FIG. 2 is the right side elevation view of the flag thereof;

FIG. 3 is the left side elevation view of the flag thereof;

FIG. 4 is a front elevation view of the flag thereof;

FIG. 5 is the top elevation view of the flag thereof;

FIG. 6 is the bottom elevation view of the flag thereof;

FIG. 7 is an isometric view of the left side and front of the flag thereof; and,

FIG. 8 is an isometric view of the right side and front of the flag as it is mounted onto the lid of a medication cup and a medication label has been located onto the flag as it would be used, thereof.

In the drawings, the broken lines illustrate environment and form no part of the claimed design.
